(57) **CLAIM**

The ornamental design for a litter scooper stand, as shown and described.

DESCRIPTION

FIG. 1 shows a top and side perspective view of a litter scooper stand showing my new design.

FIG. 2 is a bottom and side perspective view thereof.

FIG. 3 is a top plan view thereof.

FIG. 4 is a bottom plan view thereof.

FIG. 5 is a first side elevation view thereof, the opposite side elevation view being a mirror image thereof.

FIG. 6 shows a second side elevation view thereof, the opposite side elevation view being a mirror image thereof; and,

FIG. 7 shows a cross section of section line 7-7 of FIG. 3.

1 Claim, 7 Drawing Sheets(56)
